PREPARATION OF CATALYTIC FEED STOCKS FROM HEAVY HYDROCARBONS

Homer Z. Martin, Cranford, James W. Brown, Elizabeth, and Harvey E. W. Burnside, Locust, N. J., assignors to Esso Research and Engineering Company, a corporation of Delaware

Application September 4, 1951, Serial No. 244,968

3 Claims. (Cl. 196—49)

This invention relates to a process for the production of valuable distillates by partial evaporation and coking of heavy or residual hydrocarbons and by subsequent catalytic cracking of the vaporized products. More specifically the invention relates to a combination process wherein a vapor fraction suitable as a catalytic cracking feed stock is obtained by briefly contacting a residual oil with a hot medium under conditions conducive to minimizing thermal cracking. The resulting vapors are promptly passed to a catalytic cracking zone before they become substantially degraded by undesirable polymerization reactions or by thermal cracking, while additional amounts of distillate are obtained from the unvaporized portion of the residual oil as well as from any recycle stock by "drying" or coking in a dense fluidized bed of finely divided solids.

Continually increasing demand for distillates such as high quality gasoline and gas oil has stimulated efforts toward adapting relatively undesirable heavy residues such as topped or reduced crude or various analogous pitches for eventual use in catalytic cracking processes. However, because of the excessive carbon forming tendencies of these materials and their high content of catalyst contaminants, their direct use in catalytic processes has proved impractical. Accordingly, efforts to utilize these materials have largely consisted of segregating therefrom thermal gasoline and relatively light gas oil fractions by various applications of vacuum flashing or coking or both, only the gas oils having been considered as satisfactory feeds for catalytic conversion. However, conventional vacuum flashing has been only moderately successful to date since at the usual vacuum still temperatures of about 700° F. the yield of low value bottoms product is quite high, whereas at higher distillation temperatures the problem of maintaining a satisfactory vacuum becomes most difficult. Moreover such high temperature distillate product has been found to be of substantially poorer quality because of fairly extensive thermal cracking which unavoidably occurs in conventional high temperature distillations.

The various techniques previously proposed for the conversion of residual oils by coking also have left much to be desired. For instance, coking at about 950° F. has been found to produce a fairly desirable feed stock for catalytic cracking, but the rate of reaction is very slow so that it is necessary to provide large, costly reactor vessels. Also, where the usual fluid solids technique is employed, a large solids hold up for fluidization is also required and occasional fluidization difficulties may be encountered. On the other hand, when higher coking temperatures such as 1100° F. are employed so as to obtain an increased rate of reaction, difficulties are encountered in devising a practical method for removing the resulting vapors from the coking zone before they become degraded by various after-reactions. Specifically, it has been determined that an excellent feed stock for catalytic cracking can be obtained by coking residual oils at 1100° F. in a fluid bed, if the vaporized feed is removed

2

from the fluid bed and quenched, and preferably introduced in less than one second into the catalytic cracking zone. However, it is apparent that this is not feasible in conventional operation with deep fluidized beds which hold a considerable amount of the vapors for up to 15 or more seconds in a dilute phase above the bed before the vapors are disengaged and withdrawn. The dilute phase is incorporated in the usual fluid bed reactor to decrease entrainment of powdered solids in the gaseous reaction products.

It has also been proposed previously to minimize undesirable thermal cracking in the conversion of residual oils by employing a two-step process wherein the feed is first subjected to high temperature for a brief period, followed by separation of vapors and further coking of the unvaporized portion of the feed, all vapors being finally fractionated to yield the desired distillate fractions such as thermal gasoline and gas oil for use as a catalytic cracking feed stock. However, even this process has had certain shortcomings since the resulting products, and especially the catalytic cracking feed stocks, have been found to degrade appreciably not only during distillation but even on standing at room temperature.

It has now been found that residual oils can be converted to valuable products in a process in which they are treated first under conditions leading to very rapid volatilization with a minimum of thermal degradation, followed by thermal cracking of the unvaporized portion of the oil to produce additional vapors suitable as catalytic feed stock; and further followed by prompt catalytic cracking of the overhead products thus formed. Minimizing of the time involved in transporting the volatilized feed to the catalytic cracking zone is one of the major points of this invention.

The first step of this process may take several forms, depending on the means chosen for the attainment of maximum rapid volatilization. One convenient way is treatment at relatively high temperature, say 1050 to 1150° F. at substantially atmospheric pressure, in a so-called transfer line fluid solids contactor. The time of exposure of the bulk of the vapors to this temperature is limited to a maximum of about $\frac{1}{10}$ of a second at temperatures of about 1150° F. or about 1 to 3 seconds at lower temperatures such as 1050° F. In this step the residuum is contacted with inert powdered solids on which the usual carbonaceous material, which is formed as one of the products of this kind of operation, is deposited. In addition, the metallic constituents which cause considerable deactivation of the catalyst in the subsequent operation are also deposited on the inert solid and, in this way, are effectively prevented from entering the catalytic conversion zone. The inert solid material in this invention is generally circulated along with the residuum, and has the further purpose of supplying the heat for the vaporization and mild cracking of the feed stock.

The second form of the first step of this invention consists of a lower temperature treatment of the residuum, say 850 to 1000° F. Although the time of contact is maintained low, as in the higher temperature treatment, it is not necessary to maintain it quite as low as in the higher temperature treatment, and contact times of up to about 5 seconds may be permissible at about 850° F. However, in order to attain the desired high degree and high rate of vaporization, large quantities of inert gas are used to reduce the partial pressure of the hydrocarbon feed or instead a relatively high vacuum, which may range from about 0.5 to 5 inches Hg, may be applied to the vaporizing zone. This second method of treatment may include the circulation of solid particles on which coke and metallic impurities may be deposited, or in some cases this coke circulation may be dispensed with.

In both of these vaporizing operations, a residual

amount of unvaporized oil will remain, which may range from about 2 to 20 weight percent of the feed in the case of the so-called high temperature treatment and may range up to about 50 or 60% of the feed in the so-called low temperature treatment. In most of these schemes, since coke or a similar inert solid is circulated, this residual oil will be deposited on this solid. It is then necessary and desirable to provide equipment for further converting the unvaporized oil and for drying this oily coke so that the latter may be reused in the process. This is done by providing a so-called coker or coke-drying vessel in which the coke may be held for a sufficiently long time to take care of this function. It will be seen then that the present invention has a dual aspect, the principal one being the vaporization of the residuum under relatively mild conditions to obtain a catalytic feed stock and the other being the drying of the coke required in the process. However, since the former aspect requires a short vapor contact time while the latter requires a long holding time for the coke particles, part of this invention consists in the separation of these two operations whose requirements are almost mutually exclusive.

It has been found in addition that the relatively large coke-drying vessel may simultaneously serve another useful function, namely, the thermal cracking of other more refractory stocks. In practically every refinery materials of this kind are available, which could be transformed to useful final products by severe thermal treatment. One of these is the so-called clarified oil, the bottoms product from catalytic cracking of gas oils. Other materials might be the recycle streams from a coking operation, or the bottoms product of thermal cracking.

In particular it has been found that by passing the entire vaporized portion of the feed, including relatively heavy fractions, directly to the catalytic cracking zone without allowing any appreciable thermal cracking, a catalytic cracking feed stock is obtained which, in spite of the very high end point of the feed stock charged to the catalytic zone, surprisingly results in low enough catalytic coke production therein to be commercially attractive. Also, somewhat unexpectedly, the catalytic feed stock obtained in accordance with this invention produces higher yields of higher octane number gasoline than when only a gas oil fraction is conventionally fed to the catalytic cracking zone after fractional distillation of the vaporized feed into various fractions ranging from fixed gas to heavy bottoms. It seems that not only does such intervening fractionation harm the stock by allowing certain polymerization and thermal cracking reactions to occur, but the presence of the fixed gas and gasoline in the catalytic zone apparently improves the antiknock characteristics of the catalytic gasoline produced from the gas oil fraction present in the vaporized feed. Moreover, especially good results may be obtained in this connection by injecting cracking catalyst into the aforesaid vaporized hydrocarbon fraction as soon as practicable after removal of the latter from the vaporization line and before the vaporized fraction is introduced into the catalytic cracking zone proper. A further advantage can be obtained by simultaneously feeding different feeds at proper points in the novel process. For example, a readily crackable feed such as reduced crude may be fed to the quick-conversion transfer line while a more refractory stock such as clarified catalytic cycle oil may be fed directly to the fluid coking zone along with the unvaporized portions of the reduced crude.

Accordingly, it is an object of the present invention to improve the yield and quality of gasoline and gas oil from residual oils. A more specific object is an efficient vaporization of residual oils to produce high yields of valuable distillates suitable for catalytic cracking while only the heaviest residual materials are cracked thermally.

Still other objects as well as the general nature of the

invention will become apparent from the subsequent description wherein reference is made to the accompanying drawing. In all figures of the drawing the same numerals are used to designate the same or analogous pieces of equipment.

Fig. 1 is a semi-diagrammatic illustration of a system suitable for carrying out one preferred embodiment of the invention wherein hot solids are briefly mixed in a transfer line with heavy feed, partially to volatilize the latter rapidly by straight evaporation and some very mild thermal cracking. The resulting vapors are charged to catalytic cracking equipment. The solids, containing some unvaporized oil, are sent to a coke drying vessel.

Fig. 2 shows a similar system wherein the hot solids are removed from the fluidized zone by overhead entrainment into a superposed transfer line.

Fig. 3 shows an alternative system employing a fired coil and a vacuum transfer line to accomplish the partial evaporation with a minimum of coking.

Fig. 4 shows a system wherein the partial evaporation and incidental mild coking is obtained by contacting the feed with hot flue gases.

Referring now in detail to Fig. 1 of the drawing as an example, a pitch or reduced crude such as an 8% bottoms fraction characterized by a Conradson carbon of about 10 to 30 weight percent and about 5° A. P. I. gravity, and obtained by vacuum distillation of a West Texas crude is used as feed. This feed is supplied at about 300 to 800° F., or preferably at about 650 to 750° F. through line 1 into transfer line vaporizer 2 which is maintained at a temperature of about 1050 to 1100° F. Finely divided inert solids such as petroleum coke particles having an average diameter up to about 500 microns, preferably between about 100 and 300 microns and heated to a temperature between about 1100 and 1500° F. are also introduced into the vaporizer line 2 through line 3 in a ratio of about 5 to 50 lbs. of solids per pound of pitch. As a result, the mixture of solids and hydrocarbon feed in line 2 will attain a temperature of about 1050 to 1100° F., and is allowed to remain in the vaporizer line 2 for a period not in excess of about 2 to 5 seconds, preferably between 0.5 and 1 second, as otherwise an uneconomical amount of the feed would be converted to dry gas.

The effect of vapor residence time and temperature on conversion of West Texas vacuum pitch to dry gas is shown in Table I below. In general, residence times are chosen so as to yield less than 10 weight percent, and preferably less than 5 weight percent of dry gas on feed, somewhat longer residence times being permissible at lower temperatures as shown in Table I.

TABLE I

Temperature, ° F.	Time to Yield, 5 wt. percent Dry Gas on Feed, Secs.	Time to Yield, 10 wt. percent Dry Gas on Feed, Secs.	
		1,050	1,100
1,050	1.0	1.0	5.0
1,100	0.8	0.8	2.0

Typical vapor velocity through vaporizer line 2 may range between about 10 and 100 feet per second, and an inert diluent gas such as steam may be introduced through line 9 simultaneously with the feed in order to aid in the control of vaporization and of contact time.

In vaporizer line 2 a substantial portion of the liquid feed is vaporized while the unvaporized portion remains in contact with the solid particles. From vaporizer line 2 the partially vaporized mixture of feed and solids is passed through a dust separator such as cyclone 4 wherein the solid particles surrounded by unvaporized feed are separated from the vaporous portions of the mixture. The total vaporized product is passed through line 5 to a catalytic cracking unit 6 where, under conditions well known per se, it is converted to desirable distillate frac-

tions such as gasoline and heating oil. The desired fractions may be isolated from the cracked vapors in distillation tower 7 and other conventional recovery equipment (not shown). The bottoms fraction obtained in the fractionation tower, and usually referred to as clarified cycle oil after settling or other separation of the entrained catalyst therefrom, may be returned to the process and coked as later described in greater detail. The catalytic cracking unit may preferably be a conventional fluid bed, though some of the important advantages of the present invention may be obtained also with other known types of catalytic units such as the so-called "suspensoid" units wherein a finely divided catalyst is employed in the feed vapors in the form of a dilute suspension; or with a moving bed or a fixed bed unit.

However, it is essential to the success of the present invention not only to keep the residence time in the transfer line 2 in the neighborhood of one second or less, but also to prevent thereafter any undesirable thermal reactions from occurring in the liberated vapors before the latter are brought into the catalytic conversion zone. To this end it has been found especially advantageous to inject finely divided cracking catalyst through line 8 into the vapors in line 5 as soon as the latter are separated in cyclone 4 from the inert solids and unvaporized feed, so that whatever cracking occurs in the hot vapors during passage to the catalytic cracking unit is of the desirable catalytic type rather than the inferior thermal type. This procedure has been found particularly convenient in systems employing so-called fluid catalytic cracking units, in which case some active catalyst, preferably catalyst freshly regenerated in a conventional fluid combustion unit (not shown), may be readily introduced through line 8 and mixed with the hydrocarbon vapors in line 5 in a ratio of about 5 to 20 lbs. of catalyst per pound of feed.

Where injection of solid catalyst through line 8 may be impractical or inconvenient, as when the catalytic cracking unit is of the fixed bed type, it is important to take other steps for minimizing degradation of the hot vapors prior to the catalytic step. This can be accomplished at least to some extent by prompt quenching of the vapors to at least 1000° F., but preferably to 900° F. or lower, which can be obtained by direct injection of cooling water or other quenching liquid through line 8, or by indirect heat exchange. However, it must be pointed out that these alternatives are not true equivalents of the aforementioned catalyst injection, promptly after vaporization of the feed. On the contrary, even if the volatilized feed portion is promptly quenched, mere standing or storage of such a quenched feed at room temperatures has been found to cause a loss of some of its favorable qualities as a catalytic cracking feed stock, especially with regard to dry gas formation and gasoline yield.

This is illustrated in Table II wherein catalytic cracking data are summarized for three different test runs. In each run the same feed, produced by coking a vacuum pitch at 950° F., was passed over a bed of fresh conventional silica-alumina cracking catalyst at 950° F. at 2 v./hr./v., the length of storage of the feed between its production by coking and its introduction into the catalytic cracking test being the only variable.

TABLE II
Effect of feed storage on catalytic cracking yields

Test No. Feed Storage (Hours) at Room Temp.	1 0.25	2 2.7	3 20
	Yields from Cat. Cracking		
Coke, Wt. Percent on Feed	12.3	11.2	11.5
Gas up to C ₃ , Wt. Percent on Feed	6.4	8.1	8.8
C ₄ , Vol. Percent on Feed	8.8	11.2	11.1
C ₄ –430° F., Vol. Percent on Feed	45.9	41.7	38.6
Boiling above 430° F., Vol. Percent on Feed	37.2	38.1	40.1

It will be seen that, as feed storage prior to catalytic conversion is increased, less and less of the feed is catalytically converted to products boiling below 430° F., indicating that a more refractory feed is produced during storage. Furthermore, increased length of storage of this type of feed also significantly reduces the gasoline yields at a given conversion. Consequently, it is again pointed out that while prompt quenching of the transfer line vapors is useful if catalyst injection is impractical at that stage, quenching alone gives no assurance against feed degradation as compared with the effective protection obtained by prompt catalyst injection.

The inert solids containing unvaporized oil, which oil may be equal to about 2 to 20 weight percent of the original residuum, are passed from cyclone 4 through line 10 to a fluid vessel 11 where they are dried by thermally converting the unvaporized feed to dry coke and vapors at temperatures between about 1050 and 1100° F. Steam or other inert gas is introduced into coking vessel 11 through line 13 at a rate sufficient to produce an upward superficial gas velocity of about 0.5 to 5, preferably about 1.5 to 3 feet per second so as to keep the solid particles in the form of a dense turbulent fluidized bed having an upper level 12. The average residence time of the solid particles in coking vessel 11 may range from about 1 to 10 minutes. The liberated vapors may be withdrawn from vessel 11 through line 14 and combined with the vapors flashed off in vaporizer line 2 before introduction into cyclone 4. However, especially if clarified catalytic oil or a similar refractory cycle stock is fed into vessel 11 through line 16, it may be preferable to pass the cracked vapors from vessel 11 through cyclone 17 and line 18 to a separate recovery system, rather than combining them with the hydrocarbon vapors from line 2. The high-temperature, longer time coking in vessel 11 results in a high conversion and yields a product containing more gasoline of relatively high octane number than in the transfer line, but the heavier fractions constitute a poorer catalytic feed stock. Also, diolefins such as butadiene are produced, which it is better to exclude from the catalytic cracker and subsequent refining equipment.

Some of the hot, relatively dry, coke-containing particles may be withdrawn from vessel 11 through well 30, where residual feed is stripped off by steam or the like introduced at 31, and finally the stripped, hot solids are passed back to vaporizer line 2 through line 3 as previously described. Excess coke produced in the process may be removed through line 32 or at any other convenient point.

Furthermore, coke-containing solid particles are also withdrawn from vessel 11 through well 19 and standpipe 20, preferably after being stripped of residual volatiles by introduction of steam or the like through line 21. From standpipe 20 the coked solids are passed to a heating zone 23 where the temperature of the circulating solids is raised to about 1100 to 1500° F., or sufficiently to supply the heat required by the reactions proceeding in vaporizer line 2 and coking vessel 11. This can be accomplished in any known manner as, for instance, by introducing an oxygen-containing gas such as air at 26 so that the coke from standpipe 20 is at least partially burned in transfer line 23 and the temperature of the remaining solids is correspondingly raised. Alternatively, or in addition to supplying heat by combustion of the coke produced in the process, the required heat may also be produced in an auxiliary burner 24 in which an extraneous fuel such as fuel gas introduced at 25 is burned with air introduced at 26, and the resulting hot flue gas is then contacted with the solids in line 23. As a further alternative, the transfer line burner 23 illustrated in Fig. 1 may be replaced by a fluid unit similar to vessel 11 wherein the process coke may be fluidized and burned in air in a manner well known per se. Some burning of the circulating coked solids has been found

generally beneficial since this increases the surface area of the solids and consequently facilitates feed vaporization thereon.

The heated solids from line 23 may be passed to a cyclone 27 where they are separated from the flue gases and returned through dip leg 28 to coking vessel 11 at a proper rate to maintain the desired coking temperature. Also a part of the heated solids may be allowed to bypass coking vessel 11 and introduced directly through lines 29 and steam line 9 into vaporizer line 2, which arrangement is particularly necessary when it is desired to operate the vaporizer line 2 at a higher temperature than coking vessel 11.

In Fig. 2, another suitable system is shown wherein the transfer line vaporizer is placed directly above the coking vessel so that the inert gas used for fluidizing the solids in the coking vessel can be used effectively in assisting vaporization of the feed in the superimposed transfer line. Referring specifically to Fig. 2, the residual oil is injected through feed injector 1 into vaporizer line 2 which is again maintained at a temperature between about 1050 and 1100° F. with the aid of a finely divided solid heat carrier. This heat carrier, together with steam or other inert gas and with the hydrocarbon vapors produced in vessel 11, is conveniently supplied to the vaporizer line 2 by entrainment from the coking vessel 11 located below, the total gas being sufficient to raise the superficial gas velocity in the relatively small-diameter line 2 to a value of at least about 20 ft./sec., preferably to about 35 to 50 ft./sec. Besides helping to propel the hot solids and oil feed upwardly at the desired rate, the inert gas serves the further useful function of reducing the partial pressure of the oil feed in line 2 and thereby facilitates the evaporation of the feed. In the processes illustrated in Figs. 1 and 2, about 5 to 25 weight percent of steam on residuum feed to the coker is typical. In Fig. 2, when it is desired to avoid undue condensation of the coker vapors on contact with relatively cool feed in feed vaporizing line 2, additional heat may also be supplied to line 2 by hot solids from line 29.

Following a coking period of less than 2, and preferably less than one second, the stream comprising diluent gas as well as vaporized feed and the unvaporized portions thereof which get deposited on the inert solids, is withdrawn from vaporizer 2 into a separating device such as cyclone 4. The separated vapors, which represent the desired feed stock for catalytic cracking, are withdrawn from the cyclone through line 3, and after injection of catalyst or quenching liquid at 8, are passed to the catalytic cracking unit 6 and processed in a manner analogous to that already described in connection with Fig. 1.

The solids containing the unvaporized portions of the feed, after separation from the vapors in cyclone 4, are passed through standpipe 10 to the aforementioned coking vessel 11 having a relatively large diameter. There the solids are fluidized by means of steam or a similar inert gas introduced at 13 at a rate sufficient to give a superficial upward gas velocity preferably of about 2 to 3 ft./sec., or up to about 5 ft./sec. as is well known per se. Under substantially the same conditions as described in connection with Fig. 1, the unvaporized portions of the feed are coked in the resulting dense fluid bed in vessel 11 and the resulting vapors, together with the inert gas, are passed from the fluid bed directly upward into the relatively small-diameter vaporizer line 2 previously described. In this manner, the coke or other solid particles entrained in the aforesaid vapors serve conveniently as a heat carrier for the vaporizing step proceeding in line 2. The degree of entrainment may be adjusted by varying the fluid level 12 as well as by variation of the amount of aeration steam added at 13. In general it is desirable to have a solids/oil weight ratio of at least 10:1 in the transfer line, as otherwise the solids separated in cyclone 4 tend to be too wet for permitting the desired fluidity in line 10. However, because of this high

ratio of solids to oil, in the systems shown in Figs. 1 and 2, it is impractical to remove any substantial amounts of heat from the reaction mixture between the vaporizer line and the coker, and consequently both of these zones are almost necessarily operated at very similar temperatures. Besides introducing the main feed stock at 1, other hydrocarbon feed such as recycle stock may be introduced directly into the coking vessel 11.

Relatively dry solids may be withdrawn from vessel 11 through stripping well 19 and, after mixing with air introduced at 22, some of the coke deposited in the process may be burned in combustion zone 23 and reheated solids returned through lines 28 and 29 to coking vessel 11 and/or vaporizer line 2 in substantially the same fashion as described in connection with Fig. 1. Excess process coke may be stripped of vapors in well 30 and withdrawn through line 32. The advantage of this process as compared with that illustrated in Fig. 1, is a considerably simpler flow plan while one of its drawbacks is the impossibility of treating the coker overhead separately from the directly vaporized feed portions which latter normally constitute a more desirable catalytic feed stock.

Fig. 3 shows still another system adapted for carrying out of the present invention. According to this embodiment the preheated pitch or residuum at about 700° F. is fed through line 1 to a fired coil 33 located in furnace 34. Since in this instance substantially all of the required process heat may be supplied to the liquid feed indirectly from furnace 34, only a low concentration of inert solids, such as 0.1 to 1 lb. of coke or the like per gallon of liquid feed, needs to be injected through line 3 as in established techniques of so-called suspensoid cracking, the main purpose of the inert solids being to prevent coke deposition on the coil.

When the desired temperature of vaporization, which may be between about 750 and 1000° F. is reached in the coil, the mixture of oil and solids is flashed into a vacuum transfer line 2 where about the lightest 35 to 75 weight percent of the feed vaporizes and the non-vaporized portion is immediately separated in cyclone 4. Vacuum may be created by a steam ejector 35 connected to the cyclone overhead line 5 or by other conventional means such as vacuum pumps. The absolute pressure in the vacuum line may be of the order of 0.1 to 10, or preferably 0.5 to 5 inches of mercury. The heavy distillate in line 3 is pumped to about atmospheric pressure by pump 36, and otherwise treated in substantially the same manner as described in connection with Fig. 1. Cracking catalyst may be added through line 8. The solids concentration in the unvaporized feed portion in line 10 is maintained sufficiently low to permit pumping of the resulting suspension or slurry back to about atmospheric pressure and it is introduced into coking vessel 11 wherein the unvaporized feed is substantially completely coked or thermally cracked in a dense turbulent bed of inert solids fluidized with the aid of steam or other inert gas introduced at 13. Unlike in the previously described systems, the low solids/oil ratio in line 10 of Fig. 3 permits a fairly independent adjustment of the respective temperatures in line 2 and coker 11. In alternate methods of operation sufficient solids may be circulated so that the residual unvaporized oil forms a relatively low proportion of the mixture being passed to coker 11 and may be handled by a screw conveyor, or if the mixture is actually free flowing, the solids may be circulated from vessel 4 to vessel 11 by means of fluidized standpipes.

From coker vessel 11 solid coke, after stripping in withdrawal well 30, may again be mixed with steam introduced at 9 and circulated back through line 3 for admixing with fresh feed. Net coke may be withdrawn at 32 while coking products may be withdrawn through line 14 and processed further as previously described with reference to Fig. 1. Also, where desired, additional

heat may be supplied to the fluid bed in coker vessel 11 by burning and recirculating some of the coke in lines 20, 23 and 28 in the manner described in detail in connection with Fig. 1. In fact, furnace 34 may be entirely replaced by this heating apparatus. Alternatively, heat may also be supplied in this or the other herein described embodiments by direct or indirect heat exchange of the fluidized solids in vessel 11 with hot regenerated catalyst from the catalytic cracking unit, as described and claimed in copending applications Serial No. 227,169 (filed May 19, 1951), and Serial No. 230,746 (filed June 9, 1951).

Still another embodiment of the invention is represented in Fig. 4 wherein a hot extraneous gas is mixed with the pitch feed so as to vaporize the latter, the presence of the extraneous gas having an effect equivalent to vacuum flashing. Specifically, pitch or a vacuum residuum from line 1 are introduced into line 2 and mixed there with hot flue gases taken from cyclone 27 at about 1500 to 2000° F. in an amount sufficient to vaporize about 20 to 75% of the pitch. The amount of flue gases required may be such as to decrease the hydrocarbon partial pressure in line 2 to about 0.03 to 0.2 atmospheres when line 2 is operated at about atmospheric pressure. The resulting mixture of flue gas and vaporized portion of feed is immediately separated from the unvaporized feed portion in cyclone 4 and the separated gas passing through line 5 is promptly cooled by means of heat exchanger 8 to about 400° F. or lower, at which temperature substantially all of the vaporized hydrocarbon product is condensed for recovery. The liquid hydrocarbon condensate is separated from the flue gas in drum 41 and finally converted into the desired products in catalytic cracking zone 6. Any hydrocarbons contained in the uncondensed gas coming from drum 41 may be recovered by further cooling or by passing the gas stream through a charcoal adsorption plant, by oil scrubbing, or other conventional recovery system.

The unvaporized portion of the feed is removed from cyclone 4 through pipe 10 and introduced into the fluidized bed in coking vessel 11 where thermal conversion of the heavy feed into light products and coke is carried to substantial completion at about 950 to 1000° F. In the illustrated arrangement it is possible to operate coking vessel 11 at a substantially higher temperature than vaporizing line 2, since heat to the fluid bed is supplied not only in the unvaporized feed stream passing through standpipe 10, but additional heat may also be brought in directly by the circulating solids. As shown, coke may be withdrawn from the fluid bed through stripping well 19 and line 20 whereupon they are mixed in line 23 with the hot flue gas from burner 24 which may be at a temperature between about 2500 and 3500° F. or higher. The resulting direct heat exchange between the relatively cool solids and the hot flue gas desirably lowers the temperatures of the latter to about 1500 to 2000° F., thereby minimizing any local overheating when the oil feed is eventually injected into the hot flue gas in vaporizing line 2. The mixture of hot coke and flue gas in line 23 may be passed through line 37 to cyclone 27 and the separated coke returned from the cyclone through leg 28 to the fluid bed in coking vessel 11 while the separated gas stream is passed through line 36 to vaporizing line 2 where it is mixed with fresh feed as previously described.

Alternatively, the system illustrated in Fig. 4 may be operated so that the coke and flue gas mixture in line 23 is discharged directly into vaporizing line 2, by-passing cyclone 27 and returning the coke to the fluid bed only after separation in cyclone 4, together with the unvaporized feed portion. In this embodiment, a high rate of coke circulation may be desirable and consequently the flue gas may be diluted with steam introduced at 38 so as to provide sufficient gas for lifting. In such an instance, the temperature of the coke and gas mixture in line 23 may accordingly be about 950 to 1100° F. prior

to injection into the vaporizing line 2. This further minimizes local overheating of feed and also provides considerable surface area for the evaporation of hydrocarbons. Vaporization in transfer line 2 and thermal cracking in vessel 11 would occur here at approximately the same temperature.

A still simpler modification of the system illustrated in Fig. 4 may omit all coke circulation and pass hot flue gas from burner 24 through line 23 directly into vaporizing line 2, without any admixing with solids. Where the vaporization of feed in line 2 is thus carried out at about 750-1000° F. or higher, the sensible heat in the unvaporized portion of the feed will be sufficient to operate coker 11 at or above 850° F. without further addition of heat. Of course, a somewhat greater danger of overheating is present when hot flue gases coming from the burner are thus injected directly into the vaporizing line, than when the temperature of the gases is first reduced by heat exchange with the coker solids.

20 The various processes just described with reference to Fig. 4 not only provide a cheap alternative for vacuum flashing followed by coking of the vacuum pitch, but also permit a larger fraction of the crude to be taken overhead as distillate product for use as feed stock in catalytic cracking. For instance, it will be seen by consulting a hydrocarbon vapor pressure chart that a temperature of 950° F. and a partial hydrocarbon pressure of 0.064 atmospheres in vaporizing line 2 corresponds to a distillate having a normal boiling point of over 1200° F. Use of a transfer line allows such vaporization to be carried out so quickly that the amount of undesirable thermal cracking is negligible.

It will be understood that the foregoing detailed description of several specific embodiments has been given for 35 purposes of illustration rather than limitation. Stated more generally, the invention is broadly applicable to heavy hydrocarbons unsuited for direct feed to a catalytic cracking zone because of their excessive carbon forming and/or other catalyst contaminating characteristics. Accordingly, the feed stock may be a reduced crude petroleum residue obtained by atmospheric or vacuum distillation and may represent the bottom 2 to 25 volume percent of the virgin crude distilled, or it may be a whole crude, or tar from visbreaking operations or similar tars or pitches. 45 Prior to feeding into the vaporizing zone, such heavy feed stocks are usually preheated to temperatures ranging from 200 to 1000° F., preferably 600 to 800° F., and their viscosity may be further reduced by dilution with naphtha or other light hydrocarbons.

50 The linear gas velocities in the vaporizing transfer lines may be between about 5 and 50 feet/second, and the apparent density of the mixtures in the transfer lines may range from a value corresponding to the density of an essentially solids-free gas as described in connection with 55 Fig. 4, up to densities as high as about 5 or 10 lbs./cu. ft. where vaporization of the feed is carried out in the presence of a substantial amount of solids as illustrated in Fig. 1.

In the coking vessels the existing conditions are those 60 characteristic of the maintenance of a dense, turbulent, fluidized bed, that is, the superficial gas velocity may range between about 0.5 to 5, or preferably 2 to 3 feet per second, and the apparent density of the dense bed may range between about 10 and 50 lbs./cu. ft. The residence 65 time of the unvaporized feed in the coking vessel may range from about 1 to 150 minutes depending on temperature and the refractory nature of the stock.

The inert contact solids used in the coking vessels, and in the vaporizing lines where indicated, preferably are 70 finely divided particles of petroleum coke whose diameter may range up to about 500 microns, preferably between 100 and 300 microns. Instead of coke, finely divided inorganic inert such as sand, spent clays, pumice and the like may be used similarly, except that in such cases it will 75 be preferable to burn all the coke produced in the process

and use any excess heat for steam generation or the like whereas in the case of petroleum coke, net coke product may be readily recovered in substantially pure form. The ratio of unvaporized feed to solids in the coking vessels is maintained sufficiently low to allow proper fluidization, desirable ratios being preferably not in excess of about 1 wt./wt./hr. at about 900° F. coking temperatures, or 3 wt./wt./hr. at 1000° F. coking temperatures.

Where a catalytic cracking zone of the fluid type is used, the velocity and density conditions prevailing therein are also substantially within the same range as those described above with respect to the coking vessel, as is well known per se. Moreover, despite the fact that the feed introduced into the catalytic cracking zone contains a very substantial proportion of constituents boiling well above the gas oil range, the temperature conditions are essentially the same as those used in conventional gas oil cracking, i. e., between about 800 and 1000° F. The catalyst used in the catalytic cracking zones may be any conventional cracking catalyst such as activated clay, activated alumina, synthetic composites of silica with a minor proportion of alumina, magnesia or boria, and so on.

Furthermore, the physical arrangement specifically described herein may be changed or modified by those skilled in the art without departing from the spirit of the present invention. For instance, while the unvaporized portion of the feed separated in cyclones 4 may be sufficiently fluid to allow transfer to the coking vessels by ordinary pumps as shown in Fig. 3, or it may contain enough dry solids to be transportable to the coking vessels in a fluid state through standpipes and the like as shown in Figs. 1, 2 and 4, relatively viscous mixtures containing unvaporized feed and inert solids may also be transported to the coking vessels with the aid of screw conveyors or the like. Also, while no specific mention thereof has been made earlier herein, when a standpipe is used to transport mixtures of unvaporized feed and inert solids from the cyclone to the coking vessel, it may be beneficial to operate with a positive pressure difference across such a cyclone standpipe so as to force the flow of the wet solids in the desired direction, thus preventing any vexatious clogging.

Finally, whenever the volatilization of liquid hydrocarbon feed in transfer line 2 has been referred to herein simply as "vaporization," it will be understood that at the temperatures employed such vaporization is inherently accompanied by some mild cracking or coking, and consequently that any hydrocarbon vapor described herein as "vaporized feed" includes not only simply evaporated feed constituents but the incidental cracking products as well.

Having given a full description of the invention and of the manner of using it, the scope of the invention is particularly pointed out and distinctly claimed in the appended claims.

We claim:

1. A process for converting a heavy hydrocarbon feed stock into lighter products which comprises passing the feed stock through a heating and vaporizing zone at a temperature in the range of 750° F. to 1150° F., whereby a portion of the feed stock is vaporized, separating the vapors from the unvaporized portion of the feed stock, immediately injecting finely divided cracking catalyst into

the separated vapors and immediately passing the mixture of vapors and cracking catalyst through a catalytic cracking zone maintained under cracking conditions, recovering cracked products including gas and gasoline from the cracking zone, introducing the unvaporized portion of the feed to a coking zone containing a dense, turbulent bed of inert solids maintained at a temperature in the range of about 850° F. to 1150° F. whereby the unvaporized feed undergoes thermal cracking in the coking zone during an average residence time of at least 1/2 minute, withdrawing thermally cracked vapors from the coking zone, passing the withdrawn thermally cracked vapors through a second catalytic cracking zone and recovering valuable distillate fractions therefrom, withdrawing solids containing coke deposited thereon from the coking zone, burning the withdrawn solids in a free oxygen-containing gas thereby raising the temperature of said solids to a temperature above 1150° F. and returning the heated solids to the coking zone.

20 2. A process according to claim 1 in which the heating and vaporizing zone constitutes a transfer line system and wherein the feed stock is contacted with hot solids during a period of time less than one second.

3. A process for converting a heavy hydrocarbon feed stock into lighter products, which comprises passing the feed stock through a heating and vaporizing zone at a temperature in the range of 750° to 1150° F., whereby a portion of the feed stock is vaporized, separating the vapors from the unvaporized portion of the feed stock, 25 immediately injecting finely divided cracking catalyst into the separated vapors and immediately passing the mixture of vapors and cracking catalyst through a catalytic cracking zone maintained under cracking conditions, recovering cracked products including gas and gasoline from the cracking zone, introducing the unvaporized portion of the feed to a coking zone containing a dense, turbulent bed of inert particulate solids maintained at a temperature in the range of about 850° to 1150° F. and for a time period sufficient to thermally crack the unvaporized feed, withdrawing thermally cracked vapors from the coking zone, 30 passing said thermally cracked vapors through a catalytic cracking zone containing cracking catalyst at cracking temperature, withdrawing solids carrying coke deposits from the coking zone, burning at least part of said coke to reheat said solids, and returning reheated solids to the coking zone to supply thermal cracking heat requirements in said zone.
